DIE ROLL AND METHOD OF MAKING
THE SAME

Frederick Ulrich, Bayonne, N. J., assignor to Conmar Products Corporation, Bayonne, N. J., a corporation of New Jersey

Application June 14, 1940, Serial No. 340,436

22 Claims. (Cl. 76—107)

This invention relates to die rolls, particularly for the rolling of slide fastener wire.

In recent years a process for making slide fasteners has been developed which includes the rolling of wire under high pressure between very small-diameter coining rolls to compress and deform the wire into a connected series of embryo slide fastener elements. This wire is subsequently severed into individual elements which are attached to a tape as they are severed from the wire. The process is described in Wintritz Patent 2,201,068 issued May 14, 1940, and entitled "Manufacture of slide fasteners."

Because of the small size of the rolls (say, one inch in diameter), and the large pressure and torque required, the rolls are preferably overhung and carried by massive shafts and bearings, the shafts being driven through heavy gearing and an appropriate countershaft. The rolls are each provided with an integrally formed sidewardly projecting shank or arbor, preferably tapered, which is received in the shaft.

The die impressions are formed in the roll by first making a master punch which is negative to a single impression, and mounting the punch in the head of a press the table of which is provided with a suitable fixture carrying the roll and arranged to rotate the same intermittently an amount equal to the spacing between die impressions. After small initial impressions have been formed entirely around the roll, the punch is fed downwardly a small amount, and this operation is repeated until the impressions are of full depth.

The primary object of my invention is to generally improve die rolls of the above described character. Another object of the invention is to facilitate the manufacture of the rolls, and a still further object is to greatly lengthen the useful operating life of the same.

To the accomplishment of the foregoing general objects, and other more specific objects which will hereinafter appear, my invention consists in the die roll elements and method steps and their relation one to the other, as herein-after are more particularly described in the specification and sought to be defined in the claims. The specification is accompanied by a drawing, in which:

Fig. 1 is a side elevation of the blank which may be used to form a die roll;

Fig. 2 is an end view of the same;

Fig. 3 is a partially sectioned side elevation showing a later step in the manufacture of the blank;

Fig. 4 is an end view of the same;

Fig. 5 is an enlarged partially sectioned end elevation of a fragment of the die roll after hobbing the coining impressions in the same;

Fig. 6 is a side elevation of a finished die roll;

Fig. 7 is an end elevation of the same;

Fig. 8 is a fragmentary view of a male die roll after hobbing and before finishing;

Fig. 9 is a similar view after finishing; and

Fig. 10 is explanatory of the method of hobbing the die roll.

Referring to the drawing, and more particularly Figs. 6 and 7, the die roll there shown

comprises a working portion 12 provided with a sidewardly extending shank 14, the latter being used because the die roll 12 and its mating die roll are relatively overhung, the shanks being received within massive shafts carried by massive bearings and driven through large gearing and a countershaft, all as is set forth in greater detail in the aforesaid Wintritz Patent No. 2,201,068. The shank 14 may be a tapered shank as shown, the illustrated example having a taper of fifteen degrees. If the tapered shank is to be drawn into the shaft by means of a threaded draw-bolt, the shank 14 is preferably drilled and threaded, as is indicated at 16. The working portion 12 has heretofore been left solid.

I have found that it is extremely beneficial to hollow the working portion 12, as is indicated by the counterbore 18. I have found that the useful operating life of the rolls is substantially increased, in fact may be doubled, by hollowing the roll as here indicated, instead of leaving the same solid. This may be considered an empirical discovery, and any explanation hereinafter given, is offered merely as of possible help in explaining the beneficial results obtained, and is not to be construed in any way as a limitation of the invention.

At the outset it should be understood that the coining impressions 20 on the roll are formed by hobbing or coining the same into the roll. Thus, referring to Fig. 10, the roll blank 22 is mounted in a special fixture carried on the table of a standard press, this fixture including centers 24 and 26 which receive the roll 22, but the latter is additionally supported against the action of the press by a special cradle or support block 28. A dog 30 is secured to blank 22 and a pilot wheel 32, the latter being mounted on a shaft 34 carrying a suitable ratchet wheel 36. The latter is operated on by a pawl (not

shown) actuated by the successive reciprocations of the press.

The slide 38 of the press carries a master punch 40 the end of which is shaped to produce one of the desired shapes or recesses in the die roll. Slide 38 is moved by a pitman 42 including a pitman screw 44 having a capstan head 46 which may be turned by a capstan bar 48. The slide 38 carries a pilot pin 50 which operates in the pilot holes extending about the periphery of pilot wheel 32.

With this arrangement the pitman screw 44 may be turned until master punch 40 just begins to indent the surface of the roll blank 22. Continued operation of the press causes fractional rotation of the roll until the initial slight impressions have been carried entirely around the roll. If desired, a counter 52 operating through link 54 from shaft 34 may be employed to stop the press after the impressions have been carried around the roll. The capstan bar 48 may then be inserted in capstan head 46 and moved slightly to advance the master punch 40 downwardly by a slight amount, whereupon the hobbing operation may be continued. This procedure is followed until the die roll impressions are of sufficient depth, the termination preferably being fixed by suitable motion-limiting blocks or stops.

Referring now to Fig. 5, the hollowed surface impression there shown corresponds to a conventional slide fastener element, the projection on the head of the fastener element being formed at the relatively deep recess 60, and the spread jaws of the fastener element being formed at the moderately deep recess 62. The shallow portion 64 cooperates with a raised portion on the mating roll to form a thin web of metal between the spread jaws of the fastener element. The deep recess 66 forms the head of the next fastener element.

The pressure of the hobbing punch (40 in Fig. 10) tends to produce a sideward and upward displacement of metal on the roll. In fact, it would be difficult, as a practical matter, to obtain a perfectly uniform series of uniformly spaced die impressions by forming any one recess to full depth before beginning the next adjacent recess. It is largely for this reason that the master punch is advanced only a very small amount, say a few thousandths of an inch at a time, and the entire ring of impressions is formed around the roll at each new depth before again advancing the punch.

Another, and, I believe, much more important difficulty is that the grain size of the metal is reduced to a much smaller value beneath the deeper parts of the impressions than beneath the shallow parts of the impressions, and a difference in grain size may remain despite all efforts at normalizing the metal after finishing the hobbing operation.

In accordance with my invention, the roll is hollowed or provided with a relief hole instead of being left solid. This facilitates inward displacement of metal, that is, it provides a better outlet for movement of the metal than when using a solid roll. Thus, in Fig. 5, the initial internal diameter of the roll may be that indicated at 70. The internal diameter at the impressions may be reduced to that shown at 72 after completion of the hobbing operation. The fact that hollowing the roll lessens the upward displacement of metal, may be seen by comparison of a solid and a hollow roll after the hobbing

operation, for the latter evidences only a slight upward displacement of metal, while the former evidences a greater displacement of metal. Moreover, careful measurement will show the change in internal diameter of the hollow roll here indicated by the lines 70 and 72. I believe there is also less change in the grain size of the metal and less distortion and strain within the metal. Thus the product is a better product after normalization, and in actual practice, I have found an astonishing increase in the useful operating life of the die rolls, the life being increased about one hundred per cent.

Referring now to Figs. 1 and 2, the die roll blank 74 may be made of uniform diameter, the diameter slightly exceeding the final roll diameter. The roll is made longer than the die roll, it comprising a shank portion 76, an intermediate portion 78 which corresponds to the working portion of the roll, and an extra end portion 80 which is adapted to be cut away later, this end portion being provided so that the roll may be symmetrically supported on each side of the working portion 78 during the hobbing operation, and also to prevent excessive displacement of metal in that direction compared to the displacement in opposite direction. The blank 74 is finished on the inside, it being provided with the thread 16 previously referred to, and the hollow 18. It is also provided with tapers for centers, there being one such taper at 82 and another at 84. These tapers may have the standard sixty-degree angle, and the center used with taper 84 is preferably left small enough to be received within the internal diameter 86. A flat may be provided at 88 for cooperation with the set screw of dog 30 previously referred to. This flat disappears when the shank is later finished to the desired tapered configuration.

Figs. 3 and 4 illustrate an intermediate step which may be followed if desired. The outside surface is ground at 90 to a smooth finish and exact dimension. If desired, the part 92 may be reduced slightly in diameter so that the grinding operation may be localized to the portion 90 instead of being carried over the entire blank. The part 90 is still of excess diameter, it having substantially the same diameter as the roll in Fig. 1. It is ground merely to insure accurate seating of the roll on support 28 (Fig. 10), and accurate hobbing.

The blank is then mounted between the centers 24 and 26, as was described in connection with Fig. 10, the ground portion resting on the support cradle 28.

After completion of the hobbing operation, the blank is machined to finished dimension, as shown in Figs. 6 and 7. At this time the working portion is turned to desired diameter, the shank portion is turned to desired taper, and the excess end portion 80 (Figs. 1 and 3) is cut away.

The roll is then normalized, preferably by heating the same to a suitable temperature for 65 many hours, and then gradually lowering the temperature to normal. The normalizing process may extend over a period of, say, thirty-six hours, and is intended to improve the grain structure of the roll and to eliminate internal stresses caused by working of the metal.

The roll is then hardened. The material here employed is a tool steel, preferably a high chromium content tool steel, such as crucible "CCA" TS. With this material the roll may be 75 air-hardened, that is, heated to a suitable tem-

perature and held at the exact desired temperature, and finally cooled without necessitating quenching. The roll is then tempered, this being preferably done in an oil bath. The roll is then checked for hardness and may, for example, be given a hardness of Rockwell 61-63. The roll is then ground and polished both for the outside diameter at the working portion, and for the taper. The hollowing of the roll is probably of benefit during all of the heat treatments, as it better exposes the metal for more uniform treatment.

The invention is particularly applicable to rolls intended to accomplish relatively deep coining of irregular shapes in a wire in the course of only a single passage of the wire through the rolls. For this purpose, the rolls are preferably small in diameter. They may, for example, be one inch in pitch diameter. For such a roll I recommend an internal diameter of five-eighths of an inch. The specific roll illustrated has a pitch diameter of one inch, but an outside diameter of about $1\frac{1}{8}$ of an inch, or more exactly, 1.129 inches. The initial diameter of the blank is 1.152 inches. This is because the roll is made as a "female" roll which cooperates with a "male" roll having a smaller diameter, but with projections thereon.

The hollow or hole dimension is somewhat critical because if the internal diameter is too small, then the benefit obtained from hollowing the roll may be diminished or even lost, and on the other hand, if the wall thickness is made too small, the roll may not stand up, particularly under the hobbing operation. In other words, the diameter may be excessively reduced. This is particularly true when making the male roll for cooperation with the female roll so far described.

Thus, referring to Fig. 9, the male roll has a raised impression 94 projecting from the roll surface 96 (the latter being less than one inch in diameter). To do this, the blank is initially made of larger diameter, as is indicated at 98 in Fig. 8, and the master punch indents the material at 100 around the desired projection 94. Now, if the wall thickness of the roll is reduced too much by excessive hollowing, it will be found that the master punch will tend to indent the roll without leaving an adequate or full-size projection at 94. In other words, the inside of the roll will contract or "come together," so to speak, at an excessive rate compared to the rate of formation of the desired projection 94.

Of course, the optimum wall thickness may vary with a number of factors, such as the nature of the material used, and the size, configuration and depth of the impressions being coined in the roll. With the specific kind of roll here disclosed, I have found that the internal diameter of the roll should not be increased above the recommended diameter of five-eighths of an inch, by even so much as $\frac{1}{16}$ of an inch, for the resulting loss of wall thickness will prove noticeable when forming the male projections 94 in the manner shown in Figs. 8 and 9 of the drawing.

It is believed that the nature of my improved hollow coining roll as well as the preferred method of making the same, and the many advantages thereof, will be apparent from the foregoing detailed description. It will also be apparent that while I have shown and described my invention in a preferred form, many changes and modifications may be made without departing

from the spirit of the invention as sought to be defined in the following claims.

I claim:

1. A very small diameter die roll for deeply coining wire to a desired shape including projections and recesses along the wire, said roll being relatively free of internal stress and comprising a cylindrical working portion having a series of die impressions hobbed uniformly therearound by indenting or coining the impressions by pressure applied radially inwardly, a shank formed integrally with and projecting from a side of said working portion, the cylindrical portion of said roll being hollowed or counterbored to a diameter approximately one-half the roll pitch diameter to lessen the upward displacement of the metal during the indenting or coining operation.
2. A die roll for coining wire to a desired shape including projections and recesses along the wire, said roll being relatively free of internal stress and comprising a cylindrical portion having a series of die impressions hobbed uniformly therearound by indenting or coining the impressions by pressure applied radially inwardly, a tapered shank formed integrally with and projecting from one side of said cylindrical portion, the cylindrical portion of said roll being hollowed or counterbored to facilitate desired displacement of metal during the hobbing operation, but leaving adequate wall thickness for the hobbing and rolling operation, the hollow interior having a slight ridge or reduction in diameter within the hobbed impressions caused by hobbing of the impressions.
3. A die roll for coining slide fastener wire, said roll being relatively free of internal stress and comprising a cylindrical portion of the order of one inch in diameter having a series of die impressions hobbed uniformly therearound by indenting or coining the impressions by pressure applied radially inwardly, each impression having parts of different depth, a tapered shank formed integrally with and projecting from one side of said cylindrical portion, the cylindrical portion of said roll being hollowed or counterbored, the hole in said roll having a diameter somewhat more than one-half the pitch diameter of the roll.
4. A die roll for coining slide fastener wire, said roll being relatively free of internal stress and being made of a high chrome tool steel, said roll comprising a cylindrical portion approximately one inch in pitch diameter having a series of die impressions hobbed uniformly therearound by indenting or coining the impressions by pressure applied radially inwardly, each impression having parts of different depth, a tapered shank formed integrally with and projecting from one side of said cylindrical portion, the cylindrical portion of said roll being hollowed, the internal diameter of the hollow roll being approximately five-eighths of an inch, the hollow interior having a slight ridge or reduction in diameter within the hobbed impressions, caused by hobbing of the impressions.
5. A steel blank, for an overhung die roll having relatively deep impressions indented or coined by blows applied radially inward on its outer surface, and having a shank projecting from one side thereof, said blank being cylindrical and having a main end portion adapted to subsequently form the desired shank, and a portion adapted to subsequently form the cylindrical working portion of the roll, the working portion

being hollowed to so great an extent as to lessen sideward and upward displacement of metal during the hobbing operation and to maintain a more nearly uniform grain structure when hobbing and normalizing.

6. A steel blank, for an overhung die roll having relatively deep impressions indented or coined by blows applied radially inward on its outer surface, and having a tapered shank projecting from one side thereof, said blank being cylindrical and having a main end portion adapted to subsequently form the desired tapered shank, an intermediate portion adapted to subsequently form the end cylindrical working portion of the roll, and an end portion beyond the working portion, whereby said roll may be symmetrically supported on each side of the working portion while the latter is being hobbed to form the desired die impressions therein, the working portion being hollowed to so great an extent as to lessen sideward and upward displacement of metal during the hobbing operation and to maintain a more nearly uniform grain structure when hobbing and normalizing and the end portion beyond the working portion functioning to prevent excessive displacement of metal in that direction compared to the displacement in opposite side direction.

7. In the manufacture of hobbed die rolls by indenting or coining the same by blows applied radially inwardly on a cylindrical surface, the method which includes the step of counterboring or hollowing the die roll blank prior to hobbing the same to so great an extent as to minimize internal strains otherwise caused by the coining operation, but leaving adequate wall thickness to withstand the hobbing and subsequent die rolling operations, and keeping the same hollow during the hobbing operation.

8. In the manufacture of small diameter hobbed die rolls having a generally cylindrical working portion and a shank formed integrally therewith and projecting sidewardly therefrom, the method which includes the step of counterboring or hollowing the die roll blank prior to hobbing the same to so great an extent as to minimize internal strains otherwise caused by the coining operation, but leaving adequate wall thickness to withstand the hobbing and subsequent die rolling operations, and then coining the working portion by blows applied radially inward.

9. In the manufacture of hobbed die rolls having a small diameter working portion of the order of one inch, and including a tapered shank formed integrally therewith and projecting sidewardly therefrom, the method which includes the step of counterboring or hollowing the working portion of the die roll blank to a diameter of the order of five-eighths of the roll diameter, prior to hobbing the same, and then coining the working portion by blows applied radially inward.

10. In the manufacture of a hobbed die roll consisting of a small cylindrical portion and a shank formed integrally therewith and projecting sidewardly therefrom, the method which includes forming a cylindrical blank longer than the die roll, boring or counterboring said blank to hollow the same to so great an extent as to minimize internal strains otherwise caused by the hobbing operation, but leaving adequate wall thickness to withstand the hobbing and subsequent die rolling operations, supporting said blank at both ends in a hobbing press and hobbing the desired die impressions therearound by

blows applied radially inward at a point spaced substantially further from the end of the blank than they are intended to be spaced from the end of the roll, the excess end portion of the blank beyond the die impressions functioning to prevent excessive displacement of metal in that direction compared to the displacement of metal in the opposite direction, thereafter finish-machining the roll to cut off the excess length at one side of the die impressions, and then normalizing and hardening the roll.

11. In the manufacture of hobbed die rolls by indenting or coining the same by blows applied radially inwardly on a cylindrical surface, the method which includes the step of counterboring or hollowing the die roll blank prior to hobbing the same, to so great an extent as to minimize internal strains otherwise caused by the hobbing operation, but leaving adequate wall thickness to withstand the hobbing and subsequent die rolling operations, keeping the same hollow during the hobbing operation, coining the cylindrical surface by applying a blow radially inward, rotating the blank an amount equal to the spacing between die impressions, applying another blow radially inward, and so on until the blank has been turned through one or more revolutions.

12. In the manufacture of small diameter hobbed die rolls having a generally cylindrical working portion and a shank formed integrally therewith and projecting sidewardly therefrom, the method which includes the step of counterboring or hollowing the die roll blank prior to hobbing the same, to so great an extent as to minimize internal strains otherwise caused by the hobbing operations, but leaving adequate wall thickness to withstand the hobbing and subsequent die rolling operations, coining the cylindrical surface by applying a blow radially inward, rotating the blank an amount equal to the spacing between die impressions, applying another blow radially inward, and so on until the blank has been turned through one or more revolutions.

13. In the manufacture of hobbed die rolls having a small diameter working portion of the order of one inch, and including a tapered shank formed integrally therewith and projecting sidewardly therefrom, the method which includes the step of counterboring or hollowing the working portion of the die roll blank to a diameter of the order of five-eighths of the roll diameter, prior to hobbing the same, coining the cylindrical surface by applying a blow radially inward, rotating the blank amount equal to the spacing between die impressions, applying another blow radially inward, and so on until the blank has been turned through one or more revolutions.

14. In the manufacture of a die roll consisting of a small cylindrical portion and a shank formed integrally therewith and projecting sidewardly therefrom, the method which includes forming a cylindrical blank longer than the die roll, boring or counterboring said blank to hollow the same, supporting said blank at both ends in a hobbing press and hobbing the desired die impressions therearound at a point spaced substantially further from the end of the blank than they are intended to be spaced from the end of the roll, the hobbing operation being performed by coining the cylindrical surface by applying a blow radially inward, then rotating the blank an amount equal to the spacing between die impressions, applying another blow radially inward, and so on until the blank has been

turned through one or more revolutions, thereafter finish-machining the roll to cut off the excess length at one side of the die impressions, and then normalizing and hardening the roll.

15. In the manufacture of hobbed die rolls by indenting or coining the same by blows applied radially inwardly on a cylindrical surface, the method which includes the step of counterboring or hollowing the die roll blank prior to hobbing the same, to so great an extent as to minimize internal strains otherwise caused by the hobbing operation, but leaving adequate wall thickness to withstand the hobbing and subsequent die rolling operations, keeping the same hollow during the hobbing operation, coining the cylindrical surface by applying a blow radially inward, rotating the blank an amount equal to the spacing between die impressions, applying another blow radially inward, and so on until the blank has been turned through one or more revolutions, thereupon applying a blow more deeply radially inward, rotating the blank, and so on until the blank has been turned through one or more revolutions, and repeating this process until the die impressions have been struck inward to desired full depth.

16. In the manufacture of small diameter hobbed die rolls having a generally cylindrical working portion and a shank formed integrally therewith and projecting sidewardly therefrom, the method which includes the step of counterboring or hollowing the die roll blank prior to hobbing the same, to so great an extent as to minimize internal strains otherwise caused by the hobbing operation, but leaving adequate wall thickness to withstand the hobbing and subsequent die rolling operations, coining the cylindrical surface by applying a blow radially inward, rotating the blank an amount equal to the spacing between die impressions, applying another blow radially inward, and so on until the blank has been turned through one or more revolutions, thereupon applying a blow more deeply radially inward, rotating the blank, and so on until the blank has been turned through one or more revolutions, and repeating this process until the die impressions have been struck inward to desired full depth.

17. In the manufacture of hobbed die rolls having a small diameter working portion of the order of one inch, and including a tapered shank formed integrally therewith and projecting sidewardly therefrom, the method which includes the step of counterboring or hollowing the working portion of the die roll blank to a diameter of the order of five-eighths of the roll diameter, prior to hobbing the same, coining the cylindrical surface by applying a blow radially inward, rotating the blank an amount equal to the spacing between die impressions, applying another blow radially inward, and so on until the blank has been turned through one or more revolutions, thereupon applying a blow more deeply radially inward, rotating the blank, and so on until the blank has been turned through one or more revolutions, and repeating this process until the die impressions have been struck inward to desired full depth.

18. In the manufacture of a die roll consisting of a small cylindrical portion and a shank formed integrally therewith and projecting side-

wardly therefrom, the method which includes forming a cylindrical blank longer than the die roll, boring or counterboring said blank to hollow the same, supporting said blank at both ends in a hobbing press and hobbing the desired die impressions therearound at a point spaced substantially further from the end of the blank than they are intended to be spaced from the end of the roll, the hobbing operation being performed by coining the cylindrical surface by applying a blow radially inward, then rotating the blank an amount equal to the spacing between die impressions, applying another blow radially inward, and so on until the blank has been turned through one or more revolutions, applying a blow more deeply radially inward, then rotating the blank, and so on until the blank has been turned through one or more revolutions, and repeating this process until the die impressions have been struck inward to desired full depth, thereafter finish-machining the roll to cut off the excess length at one side of the die impressions, and then normalizing and hardening the roll.

19. A relatively stress-free hollow die roll made in accordance with the method of claim 7.

20. A relatively stress-free die roll having a hollow working portion, the exterior of said die roll having impressions indented therein by coining pressure exerted from the outside towards the inside, the hollow of said die roll being of a size sufficiently large as compared to the roll diameter to facilitate the displacement or flow of the metal inwardly during indentation of the exterior and to help provide the stress-free characteristic but leaving adequate wall thickness for the indenting and rolling operations, and the interior of the die roll having a slight ridge or reduction in diameter at the impressions, caused by the indenting of the exterior.

21. A small die roll relatively free of internal stress, said die roll having a hollow working portion the outside diameter of which is of the order of one inch, the exterior of said die roll having impressions indented therein by coining pressure exerted from the outside towards the inside, the hollow of said die roll being of a size to facilitate the displacement or flow of the metal inwardly during indentation of the exterior and to help provide the stress-free characteristic but leaving adequate wall thickness for the indenting and rolling operations.

22. A relatively stress-free die roll for coining wire to a desired shape including projections and recesses along the wire, said roll comprising a working portion having a series of die impressions hobbed uniformly therearound by indenting or coining the impressions by pressure applied radially inwardly, and a shank formed integrally with and projecting from a side of said working portion, the working portion of said roll being hollowed, the hollow of said working portion being of a size sufficiently large as compared to the roll diameter to facilitate the displacement or flow of the metal inwardly during the indenting or coining of the working portion but leaving adequate wall thickness for the indenting and rolling operations, the hollow interior having a slight ridge or reduction in diameter within the hobbed impressions, caused by hobbing the impressions.

FREDERICK ULRICH.
